UNITED STATES PATENT OFFICE.

PERCY H. THOMAS, OF UPPER MONTCLAIR, NEW JERSEY.

INSULATOR.

1,326,308.

Specification of Letters Patent.

Patented Dec. 30, 1919.

Application filed February 12, 1916. Serial No. 77,858.

To all whom it may concern:

Be it known that I, PERCY H. THOMAS, a citizen of the United States of America, and a resident of Upper Montclair, county of Essex, State of New Jersey, have invented certain new and useful Improvements in Insulators, of which the following is a specification.

This invention relates to insulators and particularly to the type adapted to electric transmission lines.

More specifically the present invention is in its preferred forms a development of the types of electrical insulators shown and described in my Letters Patent, title, Electric insulators, No. 1,250,387, dated Dec. 18, 1917, and title, Electric insulators, No. 1,273,015, dated July 16, 1918. Such preferred forms may be described as comprising a hollow, usually tubular, substantially cylindrical body portion of porcelain or other suitable vitreous material and end pieces usually of metal of suitable construction to attain the objects of effectually distributing the stresses on the porcelain or glass tube to preclude fracture or rupture of the same and maintain secure mechanical connection between such end piece and the hollow, vitreous body while precluding puncture of the insulating vitreous portions during abnormal as well as normal electrical conditions. I have found it desirable to construct such end pieces in the form of substantially conical caps preferably of cast steel having inner and outer flanges for effecting mechanical connection with the vitreous body and relating such metallic portions of the end pieces with respect to one another to insure absence of destructive arcing within the interior of the hollow vitreous body. The provision of an eye or ring member on one end piece and a clevis member on the other end piece enables the insulator to be advantageously suspended and support the transmission line or lines.

Further features and objects of the invention will be more fully understood from the following description and the accompanying drawings in which—

Fig. 1 is a central sectional view, shown partly in elevation of one form of my invention;

Fig. 2 is a similar view of same part being broken away showing certain modifications explained more fully hereinafter;

Fig. 3 is a detail top plan view of the upper end piece;

Fig. 4 is a sectional view on line 4—4 of Fig. 3;

Fig. 5 is a bottom plan view of the upper end piece;

Fig. 6 is a sectional view of the lower end piece but showing certain recesses or perforations in the body of the same;

Fig. 7 is a bottom plan view of Fig. 6; 65 and

Fig. 8 is a sectional view of one form of my invention showing a corrugated insulator body.

Similar numerals of reference refer to 70 similar parts throughout the several views.

Referring to Fig. 1, the vitreous body portion 1 is shown as a substantially cylindrical tube of uniform interior and exterior diameters. At the upper end of body portion 75 1, there are provided preferably shallow but wide grooves 2 on the exterior and interior surfaces for the reception and retaining of cement 3 or the like for the purpose of securing the upper end piece 4 to said body 80 portion 1. I prefer for some situations to use molten lead or a mixture of lead and zinc or some other alloy in place of the cement 3. One advantage of such materials is the fact that no moisture is introduced 85 during the manufacture and it is not necessary to wait the length of time required for cement to set. Sulfur may be used to fasten the caps to the body portions in the same way. Ridges 5 may also be provided 90 on the end piece to increase the degree of connection between the cement 3 and the end piece 4. Said upper end piece 4 is shown having the outer substantially circular flange 6 and the substantially concentric 95 inner flange 7 depending from the body of the upper end piece 4. For the purpose of precluding arcing or other condition of abnormal electrical discharge within the interior of the hollow body portion 1, said 100 inner flange 7 is constructed of less length than said outer flange 6, which object is the more effectually attained by the provision of a co-operating similar construction of the lower end piece as is set forth more 105 particularly hereinafter.

The body portion of said upper end piece 4 is preferably conical and provided with ribs 8, shown as six in number and usually disposed symmetrically with respect to the 110

principal axes of said upper end piece 4, as by casting the same at equal radial relation.

The eye or ring member 9 is shown cast integral with said upper end member to enable suitable mechanical connection for suspending the insulator. The upper or exterior surface of said end piece 4 may be recessed or dished at 10 to minimize the weight of said end piece 4 but providing the required degree of rigidity and strength, which object is further enhanced by the provision of said ribs 8 and by forming the cross section of said eye or ring member 9 of the general triangular outline, as more clearly shown in Figs. 3 and 4.

The lower end piece 11 is somewhat similar to said upper end piece 4 in respect to the outer flange 12 being of greater length than the inner substantially concentric flange 13, which particular feature is shown more clearly in Fig. 6, and also with respect to the conical body portion, the ribs 14 and the dished portion 15. However, said lower end piece 11 is shown provided with the clevis member 16, of advantage for connection with the upper eye or ring member 9 of an upper insulator unit similar to that shown and described to thereby form a series of insulators as the suspension means or for similar purposes, as will be understood. The lower end piece 11 may be connected to the vitreous body portion 1 similarly as described above.

However, as shown in Fig. 6, the lower end piece, here indicated by 17, may be recessed or perforated between its respective ribs 18 to form generally a "spider" in connection with a solid central portion 19 which may be dished at 20, for the purposes set forth above. Said Fig. 6 also shows the inner flange 13 of less length than the outer flange 12 similar to the construction and for the objects described hereinbefore.

In Fig. 5 the bottom of the end piece is shown as provided with strengthening ribs 26, 26.

In the construction shown in Fig. 8, corrugations or grooves 21 or the like increase the superficial area of the exterior surface of the vitreous body portion 1, thus serving to conserve the strength of the body, to increase the leakage surface and also "break up" the drops of rain, or other form of water or equivalent liquid which may be deposited on the vitreous body portion. A special advantage of the form of construction shown in Fig. 8 is the fact that the clay blank for the tube may be formed as a plain cylinder and the grooves cut in the surface after drying and before burning. Thus no strains are introduced by twisting or forcing the wet clay. Furthermore, the grooves do not weaken the strength of the insulator as a whole, since the mechanical efficiency of the joints is not 100%, i. e., the full ten-

sion strength of the cross section of the tube cannot be developed at the joint, so that farther down the tube where the stress is equally distributed the cross section need not be so great. In Fig. 2, I also show the connection between the upper end piece 4, by means of particles 22 of crushed porcelain, sand or the like, burned or otherwise rendered integral with the body portion 1, in substitution or addition to said grooves 2 to effect connection between the cement 3 and said end piece 4. Similar means may be also employed for connecting the lower end cap.

Means are provided for discharging moisture or other vaporized liquid from the interior of the vitreous body portion 1. Such means are shown in Fig. 1, in the provision of an opening through the upper cap 4 closed by the plug 23 or other closure and also an opening through the lower cap 11 closed by the plug 24 or other closure.

In such construction, water, moisture, and the like which is collected within the interior of the hollow parts, is withdrawn through the openings in the caps by placing the insulator within a heater, or by circulating dried air through the insulator, whereupon the openings are closed by the plugs 23, 24, and preferably sealed with white lead or other sealing material. This is advisable as I have found that the presence of a small amount of moisture is very detrimental and in a number of recent instances my insulators have been exploded by an interior discharge on account of imperfect drying. Such moisture is collected during assembly by condensation of liquid incident to hardening of the cement; such construction is advantageous for effecting removal of water or the like, deposited within the interior under all conditions.

In some cases, however, it is safe and desirable to have both end caps open to permit a free circulation of air as this will give the moisture a chance to dissipate and further, in case of an internal arc, there is no tendency for the insulator to explode. Where the top cap is closed and the bottom cap is open there will be the advantage that nothing can drift in from the top while the advantage of a certain circulation of air will be retained.

In the construction shown in Figs. 6 and 7, the openings within the respective lower end pieces 11, effect the withdrawal of water or moisture whether deposited within the interior of the hollow parts during manufacture or subsequent thereto. It will be noted that with the provision of the upper end piece 4 of solid construction and the lower end piece 17 of open construction, the amount of rain or other moisture deposited within the interior of the hollow parts would be of limited amount and readily discharged.

through the openings in the lower end piece. The possibility of entry of animals or other similar foreign bodies through the open bottom end piece during use of the insulator is precluded by the presence of static voltage or leakage currents.

Referring further to the danger of permitting moisture to remain in the tube, I may use some moisture absorbing material 10 within the tube. This would provide against the failure of completely drying out the moisture in manufacture, against the "sweating" of the tube and against any tendency of dew to precipitate from the inclosed air 15 on a lowering of the temperature. Such absorbent material could be Portland cement, calcium chlorid, plaster of Paris, common salt, iron filings or any suitable deliquescent substance. Portland cement has 20 the advantage of adding no new material to the insulator when cement is used as a binder and plaster of Paris and some of the others have the advantage of not being corrosive. Such material may be placed in 25 cloth bags or sacks to prevent scattering and the bags may be either laid loosely in the tube or be attached to some point on the interior wall or on the cap.

It is usually desirable to galvanize the 30 caps, in which case if the plugs in the caps are of brass they may be sealed in by soldering.

It may also be noted that the corrugations or grooves shown outside the tube as in Fig. 35 8 may be on the inside instead or may be on both sides of the tube. If on the inside only they will tend to effect the discharge outside of the tube in case of lightning, etc.

Whereas I have described my invention 40 by reference to specific forms thereof, it will be understood that many changes and modifications may be made within the scope of the appended claims without departing from my invention.

45 I claim:

1. In an insulator, the combination of a hollow body portion of insulating material open at both ends, metal elements for closing each end of said body portion and means 50 permitting the removal of moisture from the interior of said body portion.

2. In an insulator, the combination of a hollow body portion of insulating material open at both ends, metal elements for closing each end of said body portion and means 55 in said metal elements permitting the removal of moisture from the interior of said body portion.

3. In an insulator, the combination of a 60 hollow body portion of insulating material open at both ends, a metal element closing a portion of the interior of said hollow body portion and means for permitting the removal of moisture from the interior of said hollow body portion.

4. In an insulator, the combination of a hollow body portion of insulating material open at both ends, a metal element closing a portion of the interior of said hollow body portion and means in said metal element for 70 permitting the removal of moisture from the interior of said hollow body portion.

5. In an insulator, the combination of a hollow body portion of insulating material open at both ends, a metal element closing 75 a portion of the interior of said hollow body portion and means in said metal element for permitting the removal of moisture from the interior of said hollow body portion, said means comprising an opening passing 80 through said metal element and a closure for said opening.

6. A line insulator comprising a tubular member of vitreous material, metal elements 85 respectively closing the ends of said tubular member, said metal elements having flanges disposed exteriorly of said tubular member and flanges disposed interiorly of said tubular member, said exterior flanges being of greater length than said interior 90 flanges.

7. A line insulator comprising a tubular member of vitreous material of uniform diameter and open at both ends, a metal cap at each end thereof each provided with 95 a circumferential recess to receive the walls of said tubular member, the respective walls of said recessed portion of said caps positioned interiorly of said vitreous member 100 being shorter than the walls of said recessed portion positioned exteriorly of said vitreous member.

8. A line insulator comprising a single hollow tubular member of vitreous material, a conical metal cap at each end thereof having flanges extending exteriorly and interiorly of said tubular member, attachment means secured to each of said caps and ribs on each of said caps disposed between its 110 said attachment means and its said interior flange.

9. A line insulator comprising a hollow body portion of vitreous material, a metal end piece for the same comprising an annular portion extending interiorly and exteriorly of said vitreous member, ribs extending radially inwardly from said annular member to a common point of junction and attachment means secured to said common point. 115

10. A line insulator comprising a tubular tension member of vitreous material of constant interior diameter, a conical metal cap at each end of said member having substantially concentric flanges engaging said member exteriorly and interiorly, pivotal suspension means secured to each said conical cap at the apex thereof and ribs on each said conical cap extending from the apex thereof to one of said flanges, certain por- 120 125 130 135

tions of each said cap between said apex and said flanges being recessed.

11. A line insulator comprising a tubular member of insulating material, a metal cap at each end thereof, each provided with a circumferential recess to receive the walls of said tubular member, one of said caps being adapted to seal one end of said tubular element, while the other of said caps is adapted to permit free entrance of air into the other end of said tubular member.
12. In an insulator a tubular member of

insulating material provided with grooves adjacent one end both exteriorly and interiorly and a cap for said tubular member, said cap being provided with a circumferential recess to receive the walls of said tubular member, the interior walls of said recess being provided with grooves substantially in staggered relationship to the grooves on the tubular member.

In testimony whereof I have signed this specification.

PERCY H. THOMAS.
